(57) **CLAIM**

The ornamental design for a fluid conduit transfer tip, as shown and described.

DESCRIPTION

FIG. 1 is a left side view of my new design, the right side view being a mirror image thereof;

FIG. 2 is a top view of my new design, the bottom view being a mirror image thereof;

FIG. 3 is a front left perspective view thereof;

FIG. 4 is a front view thereof; and,

FIG. 5 is a rear view thereof.

The dash-dot lines in FIGS. 1-3 represent boundary lines of the base portion and form no part of the claimed design. The portion of the fluid conduit transfer tip between the base portion and the front face forms no part of the claimed design. The relative spacing between the base portion and the front face forms no part of the claimed design. The dash-dot lines in FIGS. 1-3 represent portions of the article that form no part of the claimed design. The dash-dot line in FIG. 5 represents a boundary line of the claimed design and forms no part thereof.
